Primary Examiner — Ania Aman(74) *Attorney, Agent, or Firm* — Honigman LLP; Brett A. Krueger(57) **CLAIM**

The ornamental design for an oil pick-up assembly, as shown and described.

DESCRIPTION

FIG. 1 is bottom-rear perspective view of an oil pick-up assembly, showing our design;

FIG. 2 is a top-front perspective view thereof;

FIG. 3 is a rear view thereof;

FIG. 4 is a front view thereof;

FIG. 5 is a top view thereof;

FIG. 6 is a bottom view thereof;

FIG. 7 is a right side view thereof; and,

FIG. 8 is a left side view thereof.

The broken lines in the drawings are for the purpose of illustrating portions of the article and form no part of the claimed design.
